UNITED STATES PATENT OFFICE.

WILLIAM P. PITTS, OF INDEPENDENCE, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

1,077,639.

Specification of Letters Patent.

Patented Nov. 4, 1913.

Application filed November 8, 1911. Serial No. 659,145.

To all whom it may concern:

Be it known that I, WILLIAM P. PITTS, a citizen of the United States, residing in Independence, in the county of Jackson and State of Missouri, have invented certain new and useful Improvements in Loose-Leaf Binders, of which the following is a specification.

My invention relates to improvements in loose leaf binders.

My invention is particularly adapted for use in loose leaf binders which have two clamping members respectively carrying oppositely extending posts for supporting leaves clamped between the clamping members.

The object of my invention is to provide a novel means for securely and releasably locking together the clamping members. Another object of my invention is to provide a structure which, when the loose leaves are held clamped between the clamping members, will have a smooth exterior, so that it may be readily inserted into or withdrawn from a pocket.

Other novel features of my invention are hereinafter fully described and claimed.

In the accompanying drawings which illustrate the preferred form of my invention, Figure 1 is a perspective view of my improved loose leaf binder. Figs. 2 and 3 represent respectively plan views of the two leaf clamping members and the parts connected therewith, the covers being broken away, and leaves being shown mounted on the leaf supporting posts. Fig. 4 is a vertical section on the line *a*—*b* of Fig. 2. Fig. 5 is a vertical sectional view, enlarged, on the line *c*—*d* of Fig. 4. Fig. 6 is a vertical sectional view, reduced, taken on the plane of the line *e*—*f* of Fig. 5, the leaves being removed. Fig. 7 is a vertical sectional view, reduced, on the line *g*—*h* of Fig. 10. Fig. 8 is a vertical sectional view, reduced, on the plane of the left side of the lever 19 as viewed in Fig. 5. In this view the operating lever is shown in solid lines in the locking position, and in dotted lines in a position in which one end is slightly above the outer surface of the adjacent leaf clamping member. Fig. 9 is a perspective view, enlarged, of the two locking members, roller wedges, operating lever, and springs, the lever and one of the locking members being partly broken away. Fig. 10 is a vertical sectional view, reduced, on the plane of the

line *i*—*j* of Fig. 11, one of the roller wedges being removed, the wedge carrying member being shown partly in elevation and partly in vertical section. Fig. 11 is an enlarged view partly in side elevation and partly in vertical section on the plane of the line *g*—*h* of Fig. 10. In this view the operating lever is shown swung at right angles to the adjacent clamping plate, and the roller wedges withdrawn from the locking position. Fig. 12 is a cross section on the line *k*—*l* of Fig. 11. Fig. 13 is a perspective view, enlarged, of one of the locking members. Fig. 14 is a perspective view of the operating lever.

Similar reference characters designate similar parts in the different views.

1 and 2 designate respectively two clamping members preferably of right angled form, and having secured respectively to them oppositely extending leaf supporting posts 3, the posts of one member being, preferably, disposed out of axial alinement with the posts of the other clamping member. Hinged respectively to the clamping members 1 and 2 are covers 4 which are preferably connected to the clamping members by the usual binding material 5. 6 designates the loose leaves which are clamped between the clamping members 1 and 2 and are provided with holes 7 for receiving the posts 3.

Secured rigidly to the upper clamping member 1 by projections 8 riveted in holes provided in the member 1 is a cup shaped locking member 9, the upper open end of which is provided with the projections 8, and the lower end of which is provided with a vertical hole 10 through which is adapted to extend a locking member comprising a post 11, one end of which is secured rigidly to the clamping member 2.

Vertically movable in the locking member 9 is a wedge carrying member 12 having a vertical hole 13 therethrough in which is adapted to extend the locking member 11. The member 12 at opposite sides of the hole 13 is provided with horizontal semi-circular recesses 14, which are disposed in the outer opposite sides of the member 12 and at their inner sides intersect the hole 13. Mounted respectively in the recesses 14 are wedges comprising preferably rollers 15, which, when the member 12 is in the lower position, shown in Fig. 6, lockingly engage inclined portions 16 of opposite inner walls of the locking member 9. The inclined portions 16 are at opposite sides of the locking mem-

ber 11 and incline downwardly toward said member.

If the binder were always disposed in a position in which the members 9 and 11 are vertical, gravity alone would suffice to force the roller wedges 15 and wedge carrying member 12 to the locking position, but as the binder is designed to be held in any position, a coil spring 17 has its lower end mounted on a shoulder 18 formed by an enlargement in the upper end of the hole 13. The upper end of the spring 17 bears against the under side of the leaf clamping member 1, and the tension of the spring normally forces the member 12 to the locking position, shown in Figs. 5, 6, 7 and 10.

To withdraw the wedges 15 from the locking position to the unlocked position shown in Fig. 11 different means may be employed.

For this purpose I preferably provide a lever 19 which is mounted in a slot 20 provided in the clamping member 1. The lever 19 has an arm 21 which extends horizontally through a notch 22 provided in the upper end of one side of the locking member 9. The arm 21 is provided inside the member 9 with a vertical head 23 which is mounted in a notch 24 provided in the adjacent side of the member 12. One end and upper edge of the lever 19 is provided preferably with a notch 25 which is adapted to receive the point of a lead pencil or other article, not shown, which may be inserted in the slot 20 for the purpose of swinging the lever 19 from the position shown in solid lines in Fig. 5 to the position shown in dotted lines in said figure. When in the last named position, the lever 19 projects above the outer surface of the member 1, so that the lever may be grasped and swung to the position shown in Fig. 11. When the lever 19 is swung to the position shown in Fig. 11, the arm 21 will bear upon the member 9 and the head 23 will have engaged a horizontal shoulder 26 at the upper end of the notch 24 and forced the wedge carrying member 12 to the unlocked position, shown in Fig. 11. It will be noted that the shoulder 26, in the position shown in Fig. 11, bears against the flat edge of the head 23 at one side of the arm 21 of the lever 19. By reason of this construction, the lever 19 and member 12 are releasably and automatically held in the unlocked position until such time as the operator again swings the lever 19 to the locked position shown in Figs. 5, 9 and 10. When the last named operation is effected, the spring 17 will force the member 12 to the locking position.

In order that there may be no protruding parts extending through the clamping member 1, when the parts are in the locking positions, the arrangement of the lever 19 is such that its upper edge will be parallel with the upper side of the member 1, and,

preferably, disposed flush with the upper surface of said member. It will be noted by referring to Figs. 5 and 10 that, when the parts are in the locking position shown in Figs. 5 and 10, that the head 23 of the lever 19 does not contact with the shoulder 26 of the member 12. The lever 19 may thus be swung to the position shown in dotted lines in Fig. 8 before the member 12 will be started on its upward movement. In order that the lever 19 may be held in the position shown in dotted lines in Fig. 8, frictional means are provided comprising a flat spring 27 of bowed form, and which is disposed between the member 12 and the member 9 and has a bearing against said members. The head 23 of the lever 19 is preferably thicker than the depth of the recess or notch 24, so that when the spring 27 is mounted in the position indicated in Fig. 10, the head 23 will be pressed between the members 9 and 12. The friction exerted by means of the spring 27 is insufficient to overcome the effect of the spring 17 when said spring is compressed by moving the lever 19 to the position shown in Fig. 11, the friction effected by the spring 27 is, however, sufficient to hold the lever in the position shown in dotted lines in Fig. 8 when the lever 19 is swung to said position in the unlocking movement. After the lever 19 has been swung from the position shown in Fig. 11, the inertia of the lever 19 and member 12, when in motion under the action of the coil spring 17, will cause the lever 19 to be returned to its initial position shown in solid lines in Figs. 5, 8 and 10.

In the operation of my invention, to remove or insert leaves, the lever 19 is first swung to the position shown in dotted lines in Fig. 8, after which the lever is seized and swung to the position shown in Fig. 11. The wedge carrying member 12 will thus be moved so as to withdraw the roller wedges 15 from locking contacts with the member 11 and inclined portions 16 of the member 9. The locking member 11 may now be withdrawn from the member 9, and leaves 6 inserted or removed. The ends of the leaves 6 may have notches 28 at the ends for receiving the members 9 and 11. After the leaves have been inserted or removed, the lever 19 is swung to the locking position and the member 11 inserted between the rollers 15. The rollers 15 will permit the member 11 to move toward the member 1, but will instantly lock with the member 11 and member 9 to resist the movement of the member 11 away from the member 1. The loose leaves 6 will thus be firmly and securely held clamped between the clamping members 1 and 2.

I do not limit my invention to the specific structure shown and described, as modifications, within the scope of the appended

claims, may be made without departing from the spirit of my invention.

Having thus described my invention, what I claim and desire to secure by Letters Patent, is:—

1. In a loose leaf binder, two leaf clamping members, two locking members secured respectively to the clamping members, a wedge movable to and from a position in which it will lock the locking members against relative movement in one direction, and means including a lever adapted to be grasped and operated by hand for moving the wedge from the locking position. 70
- 10 2. In a loose leaf binder, two leaf clamping members, two locking members secured respectively to the clamping members, a rolling wedge movable to and from a position in which it will lock the locking members against relative movement in one direction, and means including a lever adapted to be grasped and operated by hand for moving the wedge from the locking position. 75
- 15 3. In a loose leaf binder, two leaf clamping members, two locking members secured respectively to the clamping members, one of the locking members having an inclined portion, a wedge movable into locked engagement with said inclined portion and the opposing locking member, and means including a lever adapted to be grasped and operated by hand for moving the wedge from said locked engagement. 80
- 20 4. In a loose leaf binder, two leaf clamping members, two locking members secured respectively to the clamping members, one of the locking members having an inclined portion, a rolling wedge movable into locked engagement with said inclined portion and the opposing locking member, and means including a lever adapted to be grasped and operated by hand for moving the wedge from said locked engagement. 85
- 25 5. In a loose leaf binder, two leaf clamping members, two locking members secured respectively to the clamping members, a wedge, yielding means for moving the wedge to a position in which it will lock the locking members against relative movement in one direction, and a lever adapted to be grasped and operated by hand for operating the said means to move the wedge from the locking position. 90
- 30 6. In a loose leaf binder, two leaf clamping members, two locking members secured respectively to the clamping members, a wedge, yielding means for moving the wedge to a position in which it will lock the locking members against relative movement in one direction, and a lever adapted to be grasped and operated by hand for operating the said means to move the wedge from the locking position. 95
- 35 7. In a loose leaf binder, two leaf clamping members, two locking members secured respectively to the clamping members, a wedge, yielding means for moving the wedge to a position in which it will lock the locking members against relative movement in one direction, and a lever adapted to be grasped and operated by hand for operating the said means to move the wedge from the locking position. 100
- 40 8. In a loose leaf binder, two leaf clamping members, two locking members secured respectively to the clamping members, a wedge, yielding means for moving the wedge to a position in which it will lock the locking members against relative movement in one direction, and a lever adapted to be grasped and operated by hand for operating the said means to move the wedge from the locking position. 105
- 45 9. In a loose leaf binder, two leaf clamping members, two locking members secured respectively to the clamping members, a wedge, spring actuated means for moving the wedge to a position in which it will lock the locking members against relative movement in one direction, and a lever adapted to be grasped and operated by hand for operating the said means to move the wedge from the locking position. 110
- 50 10. In a loose leaf binder, two leaf clamping members, two locking members secured respectively to the clamping members, a wedge, yielding means for moving the wedge to a position in which it will lock the locking members against relative movement in one direction, and a lever adapted to be grasped and operated by hand for operating the said means to move the wedge from the locking position, said lever having means by which when it is moved to a predetermined position the lever and said moving means will be held from being retracted to the locking position. 115
- 55 11. In a loose leaf binder, two leaf clamping members, two locking members secured respectively to the clamping members, a wedge, spring actuated means for moving the wedge to a position in which it will lock the locking members against relative movement in one direction, and a lever adapted to be grasped and operated by hand for operating the said means to move the wedge from the locking position, the lever having means by which when it is moved to a predetermined position the lever and said moving means will be held from being retracted to the locking position. 120
- 60 12. In a loose leaf binder, two locking members, a wedge movable to and from a position in which it will lock the locking members against relative movement in one direction, and a lever adapted to be grasped and operated by hand for operating the said means to move the wedge from the locking position. 125
- 65 13. In a loose leaf binder, two leaf clamping members, two leaf supporting posts secured respectively to the clamping members, two locking members secured respectively to the clamping members, a wedge movable to and from a position in which it will lock the locking members against relative movement in one direction, and means including a lever adapted to be grasped and operated by hand for moving the wedge from the locking position. 130

- members against relative movement in one direction, and means including a lever adapted to be grasped and operated by hand for moving the wedge from the locking position, the lever having means by which when it has been moved to a predetermined position it and the moving means will be held from being retracted to the locking position.
13. In a loose leaf binder, two locking members, a wedge, yielding means for moving the wedge to a position in which it will lock the locking members against movement relatively in one direction, and a lever adapted to be grasped and operated by hand for operating said yielding means to move the wedge to the unlocked position, the lever having means by which when it has been moved to a predetermined position it and the yielding means will be held from being retracted to the locking position.
14. In a loose leaf binder, two locking members, a wedge, spring actuated means for moving the wedge to a position in which it will lock the locking members against relative movement in one direction, and a lever adapted to be grasped and operated by hand for operating said spring actuated means to move the wedge from the locking position, the lever having means by which when it is moved to a predetermined position it and the spring actuated means will be held from being retracted to the locking position.
15. In a loose leaf binder, a clamping member having a slot, two locking members one of which is secured to the clamping member, a wedge, and means including a lever disposed in said slot for withdrawing the wedge from locking engagement with the locking members.
16. In a loose leaf binder, a clamping member having a slot, two locking members one of which is secured to the clamping member, a wedge movable to and from a position in which it will lock the locking members against relative movement in one direction, and means including a lever which is disposed in said slot for withdrawing the wedge from the locking position, the lever being movable to and from a position substantially parallel with said clamping member.
17. In a loose leaf binder, a clamping member having a slot, two locking members one of which is secured to the clamping member, a wedge movable to and from a position in which it will lock the locking members against relative movement in one direction, and means including a lever which is disposed in the slot for withdrawing the wedge from the locking position, the lever having means by which when it has been moved to a predetermined position the lever and said withdrawing means will be releasably held from retraction to the locking position.
18. In a loose leaf binder, two locking members, a wedge movable to and from a position in which it will lock the locking members against relative movement in one direction, means including a lever for withdrawing the wedge from the locking position, and frictional means for resisting swinging of the lever.
19. In a loose leaf binder, two locking members, a wedge, a wedge carrying member for moving the wedge into and from a position in which the wedge will lock the locking members against relative movement in one direction, yielding means for forcing the wedge carrying member to the locking position, and a lever adapted to be grasped and operated by hand for forcing the wedge carrying member to the unlocked position, the lever having means by which it and the wedge carrying member will be releasably held in the unlocked position when the lever has been swung to a predetermined position.
20. In a loose leaf binder, two locking members, a wedge, a wedge carrying member for moving the wedge to a position in which the wedge will lock the locking members against relative movement in one direction, yielding means for forcing the wedge carrying member to the locking position, a lever for forcing the wedge carrying member to the unlocked position, and yielding frictional means for resisting the swinging of the lever.
21. In a loose leaf binder, two locking members, a wedge, a wedge carrying member for moving the wedge to and from a position in which the wedge will lock the locking members against relative movement in one direction, yielding means for forcing the wedge carrying member to the locking position, a lever for forcing the wedge carrying member to the unlocked position, the lever having means by which when it is moved to a predetermined position it and the wedge carrying member will be releasably held from moving to the locking position, and yielding frictional means for resisting swinging of the lever.
